Primary Examiner — Marianne Pandozzi(74) *Attorney, Agent, or Firm* — Loeb and Loeb, LLP**CLAIM**

The ornamental design for an espresso coffee maker, as shown and described.

DESCRIPTION

FIG. 1 is a front view of an espresso coffee maker showing my new design;

FIG. 2 is a rear view of the espresso coffee maker of FIG. 1; FIG. 3 is a left side view of the espresso coffee maker of FIG. 1;

FIG. 4 is a right side view of the espresso coffee maker of FIG. 1;

FIG. 5 is a top view of the espresso coffee maker of FIG. 1; and,

FIG. 6 is a perspective view of the espresso coffee maker of FIG. 1.

The broken lines in the drawings are included for the purpose of illustration and form no part of the claimed design.
